UNITED STATES PATENT OFFICE

HENRY RICHMOND, OF FRENCHWOOD, PRESTON, ENGLAND

WEAVER'S SHUTTLE FOR PIRNS AND REWOUND WEFTS

Application filed March 14, 1931, Serial No. 522,722, and in Great Britain March 17, 1930.

This invention relates to weavers' shuttles of the kind in which a weft-pirn is carried in a detachable manner on a peg or skewer within the shuttle which is provided at one or both ends with a metallic nose or tip. The invention has for its object to provide an improved and simplified construction whereby the weft-carrying capacity of such shuttles will be increased.

To this end and according to the present invention the peg which carries the pirn within the shuttle is fixedly mounted on the shuttle, and means are provided for retaining or locking the pirn on the peg, such for example as one or more spring clips carried by the shuttle, and adapted to engage the end portion of the pirn so as to hold this on the peg; means are preferably embodied for locking or maintaining these parts in engagement.

The peg may be formed integral with the shuttle heel tip and conveniently means are also provided for fixing the peg and tip in position after insertion and to this end the portion of the peg which lies adjacent to the tip and passes through the nose of the shuttle may be tapered to engage closely a correspondingly tapered hole in the nose of the shuttle so that when the peg is driven into the nose it is securely wedged in position.

The pirn may have its end formed with a multilated annular flange and an annular recess behind this flange, members carried by the shuttle and formed for example either integral with the shuttle or as separate spring members mounted thereon being adapted to engage the annular recess and multilated flange. For the purpose of maintaining engagement between these members and the end of the pirn locking means may be provided, for example an automatically locking device in the form of a spring actuated plate carried on the peg and constructed and arranged so as to maintain the said parts in engagement.

Three constructions according to the invention are illustrated somewhat diagrammatically and by way of example in the accompanying drawing, in which

Figure 1 is a plan of one construction,

Figure 2 is a section on the line 2-2 of Figure 1 on an enlarged scale,

Figures 3 and 4 are views similar to Figures 1 and 2 respectively but illustrating another construction, and

Figures 5 and 6 show similar views of yet a further construction.

In the construction illustrated in Figures 1 and 2 the shuttle body A has metallic tips B one of which is provided with an integral elongated tang B¹ passing through the nose of the shuttle and projecting into the shuttle recess A¹ so as to serve as a peg for the pirn C. The tang or pirn-peg B¹ is tapered as shown, at that part which is adjacent to the tip and passes through the nose of the shuttle, this tapered part enabling the peg to be firmly wedged in the nose of the shuttle. In this construction the peg B¹ is also screwthreaded at B² to receive a lock-nut B³ which, together with washers B⁴, serves not only as additional means for locking the peg to the shuttle body, but at the same time secures in position in the shuttle spring clips D adapted to engage an annular recess C¹ formed behind a flange C² on the end of the pirn C. The lock-nut B³ may be itself prevented from working loose by a pin B⁵ carried by the shuttle body and bearing on one of the flats of the nut.

The pirn C can be readily removed by flexing one or both of the clips D outwards whereupon the pirn can be withdrawn.

The alternative construction illustrated in Figures 3 and 4 is generally similar to that above described except that, instead of a lock-nut, a spring F¹ is arranged to bear at one end on a retaining plate F and at the other end on the washers B⁴ which serve to lock spring clips D¹ to the shuttle body. The pirn C has its end formed with an annular flange C³ multilated to form flats C⁴, an annular groove or recess C⁵ being provided behind this flange. The retaining plate F is longitudinally movable on the peg and has lateral projections F² adapted to engage the multilated portions or flats C⁴, the flange C³, clips D¹ and plate F thus together forming a bayonet joint. The pirn can be removed by forcing the plate F along the peg against the

action of the spring F^1 , whereupon rotation of the pirn through 90° permits the flange C^3 to pass between the clips D^1 .

5 A modified construction is illustrated in Figures 5 and 6 in which, instead of the spring clips as above described, abutments G are provided on the interior of the shuttle adapted normally to engage behind the flange C^3 . A spring-pressed retaining plate H is 10 formed with a laterally projecting portion H^1 (Figure 6) to engage one of the flats C^4 on the pirn in a similar manner to that above described. This construction is advantageous 15 in that spring clips or the like can be dispensed with and the space for accommodating the locking means reduced accordingly, thereby providing additional space suitable for a pirn of larger capacity.

20 In a shuttle embodying the present invention it will be readily seen that the space occupied by the pirn-peg and the means for locking the pirn thereon is considerably reduced as compared with that required when the usual skewer and shuttle tongue are employed. Thus a longer pirn can be employed 25 enabling the loom to run for a longer period at a time without stopping for replenishing the shuttle.

30 What I claim as my invention and desire to secure by Letters Patent is:—

1. A weaver's shuttle for pirns and re-wound wefts comprising in combination a shuttle body, a shuttle peg fixedly mounted on said shuttle body, a retaining device carried by the shuttle for engaging the pirn to retain it on the peg and locking means for maintaining said retaining device and the pirn in engagement with each other.

35 2. A weaver's shuttle for pirns and re-wound wefts comprising in combination a shuttle body, a shuttle peg fixedly mounted on said shuttle body, and a pair of resilient clips adapted to engage on opposite sides of a pirn to retain the same in position on the shuttle peg.

40 3. A weaver's shuttle for pirns and re-wound wefts comprising in combination a shuttle body having an abutment thereon adapted to engage a pirn, a shuttle peg fixedly mounted on said shuttle body and locking means for retaining the pirn in a position of engagement with said abutment.

45 4. A weaver's shuttle for pirns and re-wound wefts comprising in combination a shuttle body and a shuttle peg fixedly mounted on said body, the shuttle body having an abutment thereon adapted to engage a pirn in one angular position of the pirn to retain the pirn on the peg and locking means adapted to maintain the pirn in its position of engagement with said abutment.

50 5. A weaver's shuttle for pirns and re-wound wefts comprising in combination a shuttle body and a shuttle peg fixedly mounted on said body, the shuttle body having

an abutment thereon adapted to engage a pirn in one angular position of the pirn to retain the pirn on the peg and resilient locking means adapted to engage the pirn to maintain it in its position of engagement with said abutment.

55 6. A weaver's shuttle for pirns and re-wound wefts comprising in combination a shuttle body, a shuttle peg fixedly mounted on said shuttle body, a retaining device carried by the shuttle for engaging the pirn to retain it on the peg and resilient locking means adapted to engage the pirn to maintain it in its position of engagement with said retaining means.

60 7. A weaver's shuttle for pirns and re-wound wefts comprising in combination a shuttle body, a shuttle peg fixedly mounted on said shuttle body, retaining means carried by the shuttle adapted to engage the pirn in one angular position of the pirn to retain the same on said peg and resilient locking means, axially displaceable on the peg, and adapted to engage the pirn to maintain the same in its position of engagement in the said retaining means.

65 8. A weaver's shuttle for pirns and re-wound wefts comprising in combination a shuttle body, a pirn therefor having at one end a mutilated annular flange, an annular recess behind the flange, a peg for carrying the pirn, fixedly mounted on the shuttle, retaining means carried by the shuttle for engaging the recess and an automatically operating locking device for maintaining the retaining means in engagement with the pirn.

70 In testimony whereof I have signed my name to this specification.

HENRY RICHMOND.
